APPARATUS FOR MARKING ARTICLES

David Denelsbeck, Huntington, W. Va., assignor
to Owens-Illinois Glass Company, a corpora-
tion of Ohio

Application August 22, 1935, Serial No. 37,354
Renewed July 16, 1937

12 Claims. (Cl. 101—124)

The present invention relates to improvements in apparatus for marking, lettering and/or otherwise decorating surfaces of various articles and particularly bottles and the like containers having cylindrical body portions. The invention is particularly concerned with an adaptation of the stenciling method and is similar in many respects to the invention disclosed and claimed in my co-pending application Serial No. 704,657, filed December 30, 1933, Apparatus for marking or decorating articles.

An object of the present invention is the provision of novel means for supporting and effecting relative movement between bottles or similar containers and the screen through which coloring material is forced in applying markings or decorations to bottles.

Another object of the invention is to generally improve and simplify the mechanism employed in apparatus of the above character.

Other objects will be in part apparent and in part pointed out hereinafter.

In the drawings:

Fig. 1 is a front elevational view of an apparatus constructed in accordance with my invention.

Fig. 2 is a top plan view thereof.

Fig. 3 is a vertical transverse sectional view with parts in elevation taken substantially along the line III—III of Fig. 2.

Fig. 4 is an end elevational view.

Figs. 5, 6 and 7 are views of a manually operable control valve for the screen frame reciprocating motor. Fig. 5 is a side elevational view thereof. Fig. 6 is a similar view taken from the opposite side of the view shown in Fig. 5. Fig. 7 is a sectional elevational view taken substantially along the line VII—VII of Fig. 6.

Fig. 8 is a view illustrating the means for supplying and regulating the supply of air under pressure to the motor employed for reciprocating the screen frame.

In more or less general terms, the apparatus includes a rotary chuck designed to support a bottle or similar container in a cumbent or horizontal position beneath a screen through which the coloring material is forced and applied to the bottle during rotation of the latter and horizontal movement of said screen. The screen and of course its supporting frame, are reciprocated horizontally relative to the bottle or other container by an air operated piston motor. Operation of both the piston motor and bottle holding chuck is controlled by a single manually operated device such for example as a treadle of the type shown.

Specifically the present apparatus includes a wheeled base 10 carrying a platform 11, or table, the latter supporting frames 12 designed to carry the bottle chuck 13 and parts directly associated therewith as will be apparent presently. These frames 12 are substantially inverted U-shape in side elevation (Fig. 1) and include a pair of vertical slideways 14 at their inner ends, said slideways being spaced apart in the direction of the length of the platform 11 and adapted to accommodate a slide 15 upon which the bottle chuck 13 is mounted. An adjusting screw 16 and hand wheel 17 at the lower end thereof, provide means whereby the elevation of the chuck may be varied to compensate for variations in the diameter of bottles or other such articles being decorated.

The chuck 13 includes inner and outer sleeves 18 and 19 respectively attached to a holder 20, said inner sleeve being tapered to fit over the neck portion of a bottle and provided with a vacuum sealing ring 21 at its outer end adapted for sealing contact with the shoulder portion of the bottle. These sleeves are threaded into the holder 20 and as is undoubtedly apparent, it is intended that the air shall be exhausted from the inner sleeve in order to securely attach the bottle to the chuck. Such exhaustion of air from the sleeve is obtained by way of an axial opening 22 in a horizontal shaft 23 which is journaled in bearings 24 at the upper end of the slide block 15, said shaft at one end being threaded into the holder 20 and at its other end carrying a grooved drum 25 or pulley. The passageway 22 in the shaft 23 opens at its inner end into an annular groove 26 provided in a stationary sleeve 27 which surrounds a portion of the shaft between the bearings 24.

A supply pipe 28 connects this annular channel or groove 26 with a vacuum tank 29 by way of a manually operated valve 30 through which the application of vacuum to the chuck is controlled. A treadle 31 is operatively connected to the valve 30 by means of a rod 32. A coil spring 33 normally holds the valve 30 in position to break communication between the chuck 13 and the vacuum tank 29.

A screen frame 34 carrying a screen 34a is attached to a pair of horizontal arms 35 and is disposed immediately above the position occupied by the bottle B which is to be decorated, said frame in this instance including a pair of longitudinal side bars 36 connected by end members 37. The arms 35 which directly support the screen 34 extend from one side of a slide 38 which is mounted for horizontal movement in the direction of the length of the platform 11, in

horizontal slideways 39, the latter provided at the upper side of the frames 12. Stops 40 near the opposite ends of the sideways limit the extent of reciprocating movement of the slide 38.

5 For the purpose of forcing the coloring material through the screen 34^a, there is provided a wiper 41 or squeegee depending from an arm 42, said arm being adjustably mounted upon a horizontal rod 43. This rod 43 is secured at its 10 inner end to a rockable bracket 44 which is pivoted through a hinge pin 45 to the frames 12. Rocking of the bracket 44 for the purpose of reversing the inclined position of the squeegee 41 is obtained by mounting upon the slide 38 a 15 pair of cams 46, said cams being spaced apart and positioned for engagement with the horizontal rod 43 at the opposite ends of the path of reciprocation of the slide. These cams 46, as is evident in view of their particular contour, 20 serve to lift the squeegee 41 away from the screen a short distance during the reversing of the position of the squeegee so that the coloring material may be uniformly distributed over the screen. For the purpose of assisting the cams 25 46 in reversing the squeegee, a stationary cam 47 is mounted upon the frames 12, said cam being formed with two straight inclined surfaces which engage the horizontal rod 43 carrying the squeegee. The rod moves from one inclined 30 surface to the other at each end of the path of reciprocation of the slide 38 and thereby insures reversal of the angular position of the squeegee.

Reciprocation of the screen frame and oscillation of the bottle B about its longitudinal axis 35 are synchronized by providing driving connection between the slide 38 and the pulley 25 referred to heretofore as forming a part of the chuck unit. To this end, a cord 48 is wrapped about the pulley 25 and has its opposite ends suitably secured 40 to brackets 49 or arms which are carried by the slide 38. Thus, it is apparent that reciprocation of the slide 38 operates through the cord 48 to oscillate the pulley 25. Corresponding oscillatory movement is thereby imparted to the 45 chuck 13 and bottle B supported therein.

Reciprocation of the slide 38 is obtained by means of a fluid operated piston motor 50 which is mounted upon the table 11 and secured thereto by means of holders 51 or clamps. The piston rod 52 is connected by means of an arm 53 to the slide 38. Air under pressure is supplied to the opposite ends of the motor cylinder 54 by way of branch pipes 55 which are of somewhat smaller diameter than a main supply line 56 through 55 which the motor is connected to an air pressure supply tank 57. Air is supplied by way of a pipe 58 including a check valve 59 and pressure reducing valve 60. A pressure gauge 61 is connected to one of the branch pipes 55. Normally, constant equal pressure is maintained at both ends of the cylinder 54 owing to the direct connection between said cylinder and the air pressure supply tank 57. Movement of the piston 52 is obtained by decreasing the pressure at the 60 opposite ends of the cylinder in alternation. To this end, the branch pipes 55 are connected by means of pipes 63 to a control valve 64 (Figs. 5 to 8, both inclusive). This valve 64 includes a rotor 65 arranged within a housing 66 and carried by a shaft 67 which at its outer end is attached to pawl and ratchet mechanism 68 serving to hold the shaft and said rotor in any adjusted position. The shaft and the rotor are rotated 65 in a step-by-step fashion for a purpose which

will be apparent presently, by means including a ratchet 69 pinned to said shaft 67 and pawl 70 engageable with the ratchet and carried by a lever 71. This lever 71 is connected through a rod 72 to the treadle 31 referred to heretofore. 5

The rotor 65 is provided with four ports 73 which are equally spaced about the rotor in proximity to its periphery and extend parallel with the axis of the latter. These ports are adapted to be brought into register one at a time 10 with exhaust ports 74 leading to exhaust pipes 75. These exhaust ports are spaced apart 135° and are disposed directly opposite the point of connection between the housing 66 and the pipes 63. Thus, it will be apparent that register of one 15 of the ports 73 with either of the exhaust ports 74 will result in an immediate drop in the pressure at that end of the cylinder directly communicating with the particular exhaust port 74. Consequently, the piston 62 will move to that 20 end of the cylinder from which the air is being exhausted. Because of the difference in capacity of the main supply pipe 56 and branch pipes 55, opening of either branch pipe 55 to the atmosphere by way of one of the exhaust ports 74 reduces the pressure in one end of the cylinder 25 below that in the other end. By reference to Fig. 8 this operation is readily understood.

In operation, a bottle is positioned in the chuck 13 as indicated particularly in Figs. 3 and 30 4. Immediately thereafter, the treadle 31 is depressed with the result that suction or vacuum is applied to the chuck and thereby securely holds the bottle therein. Simultaneously with this operation, the rotor 65 is moved 45° about its axis 35 bringing one of the ports 73 into register with one of the exhaust ports 74. As stated heretofore, this results in movement of the piston 62 to one end of the cylinder 54 whereby movement is imparted to the screen 34^a. Owing to the 40 driving connection between screen frame and the pulley 25 through said cord 48, the chuck is oscillated in synchronism with the reciprocating movement of the screen frame. The squeegee or wiper functions as is customary to force the coloring material through the screen at the proper 45 points whereby said material is applied to the bottle. Upon completion of one decorating operation, another bottle is placed in the chuck and the operation of the screen, chuck and wiper 50 will be reversed.

Modifications may be resorted within the spirit and scope of the appended claims.

I claim:

1. Apparatus of the character described, comprising, a horizontally reciprocating screen, means for reciprocating it, a rotary chuck arranged to support a cylindrical body beneath and in rolling contact with the screen and in a horizontal or cumbent position, means whereby reciprocation of the screen imparts oscillatory movement to the chuck, a squeegee arranged to force a coloring material through the screen and onto the body and a single device for controlling operation of the screen. 55

2. Apparatus of the character described comprising, a horizontally movable slide, a screen carried by said slide, means for reciprocating the slide, a squeegee arranged for wiping engagement with the upper surface of the screen, means 60 for supporting a cylindrical object in a cumbent position and in rolling contact with the lower side of the screen, including a rotary vacuum chuck, a carrier for said chuck, means for moving the carrier and chuck vertically relative to the screen 70 65 75

- and means providing operative connection between the chuck and slide whereby reciprocation of the latter imparts oscillatory movement to said chuck.
- 5 3. Apparatus of the character described comprising, a horizontally movable slide, a screen carried by said slide, means for reciprocating the slide, a squeegee arranged for wiping engagement with the upper surface of the screen, means for supporting a cylindrical object in a cumbent position in rolling contact with the lower side of the screen, including a rotary vacuum chuck, a carrier for said chuck, means for moving the carrier and chuck vertically relative to the screen,
- 10 15 means providing operative connection between the chuck and slide whereby reciprocation of the latter imparts oscillatory movement of said chuck and a single device for controlling the operation of the slide.
- 20 4. Apparatus of the character described, comprising, a horizontal screen, a horizontal slide supporting said screen, means for reciprocating the slide including a fluid operated piston motor, a rotary chuck arranged to support a cylindrical object below and in rolling contact with the screen, said chuck including a vacuum cup adapted to be telescoped over a portion of the object, means whereby reciprocation of the slide imparts oscillatory movement to the chuck, means including a valve for controlling the application of vacuum to the chuck and means including a valve for controlling operation of the motor.
- 25 5. Apparatus of the character described, comprising, a horizontal screen, a horizontal slide supporting said screen, means for reciprocating the slide including a fluid operated piston motor, a rotary chuck arranged to support a cylindrical object below and in rolling contact with the screen, said chuck including a vacuum cup adapted to be telescoped over a portion of the object, means whereby reciprocation of the slide imparts oscillatory movement to the chuck, means including a valve for controlling the application of vacuum to the chuck, means including a valve for controlling operation of the motor and a single device for controlling the operation of the two valves.
- 30 6. Apparatus of the character described, comprising, a platform or table, a framework arranged thereon including horizontal slideways at the upper end, a slide arranged for reciprocation in said slideways, a screen arranged at one side of and supported by the slide, a squeegee arranged for wiping engagement with the upper side of the screen, a rockable carrier for the squeegee, means for placing the squeegee in an inclined position with respect to the screen and for reversing the position of said squeegee upon completion of each movement of the slide, means for supporting a cylindrical object in rolling contact with the lower side of the screen and means whereby the object is oscillated about its longitudinal axis in timed relation with reciprocation of the screen.
- 35 7. Apparatus of the character described, comprising, a platform or table, a framework arranged thereon including horizontal slideways at the upper end, a slide arranged for reciprocation in the slideways, a screen arranged at one side of and supported by the slide, a squeegee arranged for wiping engagement with the upper side of the screen, a rockable carrier for the squeegee, means for placing the squeegee in an inclined position with respect to the screen and for reversing the position of said squeegee upon
- 40 completion of each movement of the slide, a rotary chuck arranged to support a cylindrical object in rolling contact with the lower side of the screen, suction means for attaching the object to the chuck and means for moving the chuck vertically with respect to the screen to thereby compensate for variations in the diameter of the object.
- 45 8. Apparatus of the character described, comprising, a platform or table, a framework arranged thereon including horizontal slideways at the upper end, a slide, arranged for reciprocation in the slideways, a screen arranged at one side of and supported by the slide, a squeegee arranged for wiping engagement with the upper side of the screen, a rockable carrier for the squeegee, means for placing the squeegee in an inclined position with respect to the screen and for reversing the position of said squeegee upon completion of each movement of the slide, a rotary chuck arranged to support a cylindrical object in rolling contact with the lower side of the screen, suction means for attaching the object to the chuck, means for moving the chuck vertically with respect to the screen to thereby compensate for variations in the diameter of the object and a manually operated device for controlling operation of the slide.
- 50 9. Apparatus of the character described, comprising, a platform, a frame rising from said platform and provided with horizontal slideways therein, a slide mounted for reciprocation in the slideways, a horizontal screen arranged at one side of and supported by the slide, a squeegee carried by said frame and arranged for contact with the upper surface of the screen, a fluid operated piston motor for reciprocating the slide, means including a manually operated valve for controlling operation of said motor, a chuck arranged to support a cylindrical object in rolling contact with the lower surface of the screen and means including a manually operated valve for controlling the application of vacuum to said chuck.
- 55 10. Apparatus of the character described, comprising, a platform, a frame rising from said platform and provided with horizontal slideways therein, a slide mounted for reciprocation in the slideways, a horizontal screen arranged at one side of and supported by the slide, a squeegee carried by said frame and arranged for contact with the upper surface of the screen, a fluid operated piston motor for reciprocating the slide, means including a manually operated valve for controlling operation of said motor, a chuck arranged to support a cylindrical object in rolling contact with the lower surface of the screen, means including a manually operated valve for controlling the application of vacuum to said chuck and a single manually actuated device for controlling operation of said valves.
- 60 11. Apparatus of the character described, comprising, a platform, a frame rising from said platform and provided with horizontal slideways therein, a slide arranged for reciprocation in said slideways, a horizontal screen arranged at one side of and supported by the slide, a squeegee carried by said frame and arranged for contact with the upper surface of the screen, a fluid operated piston motor for reciprocating the slide, means including a manually operated valve for controlling operation of said motor, a chuck arranged to support a cylindrical object in rolling contact with the lower surface of the screen, means including a manually operated valve for

controlling the application of vacuum to said chuck, a carrier for the chuck mounted for vertical movement in said frames and means for moving said carrier to thereby compensate for variations in the diameter of the object being treated.

12. Apparatus of the character described, comprising, a platform, a frame rising from said platform and provided with horizontal slideways 10 therein, a slide mounted for reciprocation in the slideways, a horizontal screen arranged at one side of and supported by the slide, a squeegee carried by said frame and arranged for contact with the upper surface of the screen, a fluid

operated piston motor for reciprocating the slide, means including a manually operated valve for controlling operation of said motor, a chuck arranged to support a cylindrical object in rolling contact with the lower surface of the screen, means including a manually operated valve for controlling the application of vacuum to said chuck, a single manually actuated device for controlling operation of said valves, a carrier for the chuck mounted for vertical movement in said frames and means for moving said carrier to thereby compensate for variations in the diameter of the object being treated.

DAVID DENELSBECK.
